CLAIM

The ornamental design for a bladder for a shoe sole, as shown and described.

DESCRIPTION

FIG. 1 is a bottom plan view of a bladder for a shoe sole showing our new design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a front elevational view thereof;

FIG. 7 is a perspective view thereof;

FIG. 8 is a cross-sectional view taken along line 8—8 of FIG. 1; and,

FIG. 9 is a cross-sectional view taken along line 9—9 of FIG. 1.

FIG. 2

FIG. 3

FIG. 4

FIG. 5

FIG. 6

FIG. 7

FIG. 8

FIG. 9
